AMMUNITION

Philip H. Burdett, Bridgeport, and Joseph H. Hodgson, Westport, Conn., assignors to Remington Arms Company, Inc., a corporation of Delaware

Application April 18, 1942, Serial No. 439,522

2 Claims. (Cl. 102—56)

1

This invention relates to ammunition, and particularly to the type of projectile of machine gun caliber adapted to ignite or explode upon impact with or after penetration of a target.

Such projectiles comprise a jacket of one of the usual materials, an apertured core partly filling the jacket and providing a space for an explosive or incendiary composition, a heel closure and a gas check. The type of gas check commonly used, comprises a thin soft metal disk, preferably lead, interposed between the upper surface of the incendiary charge and the heel closure to prevent any hot powder gas from coming into contact with the active composition. The active or incendiary composition is inserted from the heel in a loose granular condition. Inasmuch as this material does not readily transmit pressure, there may be considerable variation in the compactness of the composition in different parts of the bullet, and, by reason of this as well as inevitable variations in the quantity which is measured out for insertion in a given projectile, the explosive or incendiary composition may not entirely fill the cavity provided therefor.

It is important that no empty space remain between the rear of the explosive or incendiary charge and the gas check or between the gas check and the heel portion of the projectile for the reason that, as shown by high speed X-ray radiography, the extremely rapid acceleration of the bullet when fired displaces such charge to the rear into the empty space. Such displacement takes place with considerable violence, and, since the charge is designed to ignite or explode upon impact, the force of its impact with the heel portion of the projectile may be sufficient to explode or ignite it prematurely. The acceleration of the bullet and resulting displacement of the charge takes place during the passage of the projectile through the gun barrel where a premature explosion is not desired and may be quite disastrous. Under quantity production conditions it is quite impractical, in view of the variable factors involved, to fill the apertured cores to consistently bring the base or heel surface of each explosive or incendiary charge to a predetermined level in the core so that no space will be left between the heel surface of the charge and the gas check or between the gas check and the heel closure of the projectile. This is particularly true when the heel closure is substantially a rigid element of predetermined dimensions.

The object of the present invention is to provide a safe and satisfactory heel construction

2

for incendiary and explosive projectiles which will compensate for variations in the location of the heel surface of the charge and insure that no empty space remains at the rear thereof. A further object is to provide a heel construction which comprises an effective gas check. The invention likewise contemplates other improvements in the construction of such projectiles as will hereinafter more fully appear.

10 In the drawings:

Fig. 1 is a sectional view of an incendiary projectile embodying the invention.

Fig. 2 is a fragmentary sectional view of the end portion of a projectile at one stage in its assembly.

Fig. 3 is a fragmentary sectional elevation of the heel portion of such a projectile in one stage of its assembly.

The projectile comprises a jacket 10 of such a material as gilding metal, and a hollow cylindrical core 11 of any desired hard metal such as steel. Steel cores, however, have the disadvantage that, due to their comparatively low density, the weight of the completed projectile is 20 substantially less than the weight of other projectiles fired from the same arms and there is a corresponding departure in their trajectory. In order to give the projectile such a weight and trajectory that it can be fired at a target along with other projectiles without change of aiming point, the core is preferably made of lead which has been hardened to the desired extent by alloying with another element or elements, as for example, antimony. Moreover, such lead alloy 30 cores can be readily formed by extrusion, swaging, casting or other similar flow-forming methods and thus produced more rapidly and cheaply than cores of steel.

As clearly illustrated, the core 11 is substantially shorter than the jacket, leaving a space in the nose of the bullet in front of the core for the reception of the explosive or incendiary composition 13, which composition likewise substantially fills a longitudinal aperture 12 in the core. The 40 susceptibility of the projectile to ignition from impact is in a measure dependent upon the thickness of the portion of the jacket in front of the core. This portion of the jacket is made substantially thinner than the portion surrounding the core. To this end the jacket may be tapered through its entire length or may be tapered abruptly at the location where a thin section is 50 desired.

The entire charge of explosive or incendiary composition 13 may be loaded at one time, or the

charge may be introduced in a plurality of increments which are separately pressed into place. For a typical projectile the charge is divided into two equal increments, the material of each increment being scooped out of a receptacle and dumped into a hopper or funnel device which is applied to the open heel portion of the projectile as it is held uppermost. The charge is then compressed under a pressure between 7000 and 28,000 pounds per square inch. A convenient and satisfactory loading pressure for a typical projectile is 11,000 pounds per square inch, but the composition does not transmit pressure well, and even with accurate control of quantities and pressure there is considerable variation in the resulting volume, and hence in the position of the surface of the compacted charge in the core aperture. Theoretically, the charge should exactly fill the core aperture, leaving no empty space between the charge and the heel closure, but this desideratum cannot in practice be achieved.

The present invention comprises the discovery that any possibility of a variable space remaining in the heel portion of the core aperture can be consistently eliminated by the use of an inert granular, comminuted or pulverant material. A wide variety of materials are suitable for this purpose. The essential properties are that the material be relatively dry and granular at room temperature and that it coalesce under pressure to such an extent that it will remain in place throughout the operations and handling necessary to complete the projectile. A further desirable property is a low compressibility, it being desirable that the free surface of the compacted material be substantially flush with the heel of the core. Among usable materials there may be mentioned clay and similar materials, including pipe clay, kaolin, levigated alumina, and magnesia; starches such as potato starch and dextrine, gums and resins such as gum arabic; powdered metals such as lead, copper and mixtures thereof with other metallic or non-metallic materials; waxes such as the higher alcohols and candelilla wax; non-metallic elements such as sulfur and miscellaneous organic or metal-organic materials such as tannic acid and calcium resinate. Powdered lead, gum arabic and flowers of sulfur are particularly desirable due to their low compressibility. Powdered lead and mixtures of powdered lead with such materials as copper or lead or iron oxides or carbonates have the added advantage of a high density which has a desirable effect upon the weight and weight distribution. The powdered or granular material is preferably applied as follows, reference being made to Fig. 2.

The incendiary or explosive composition 13 having been pressed into place, leaving in the heel of the core aperture 12 a recess of variable depth, a suitable quantity of the filler material 15, adapted to coalesce under pressure, is dropped into the receptacle formed by the open heel portion of the extending jacket 10. A punch 16, of the same contour and slightly larger than the core aperture 12, is then applied and brought to the position of the core heel 14, compacting and coalescing the loose filler material into the recess in the rear of the charge 13 and leaving its free surface flush with the surface 14. The punch is then withdrawn and the excess of filler material lying loosely in the open end is removed.

The heel of the bullet may be closed in any desired manner as, for example, by inserting a suitable disk of lead into the open end of the jacket and swaging the extending heel portion thereof over such disk.

To insure against forward displacement of the core 11 relative to the jacket 10, and the possibility of premature explosion under firing pressure, a disk of a harder metal, such as steel, as well as a lead disk, may be utilized. Such a construction in process of assembly is shown in Fig. 3. The charge covering body 15 of filler material has been pressed into place with its free surface flush with the surface 14. A steel disk 17 is placed upon this surface and a lead disk 18 superposed upon the steel disk. A die 19 of suitable configuration is then applied to turn the end of the jacket 10 inwardly and distort the lead disk 18 to bring its exterior surface substantially flush with the exterior surface of the in-turned portion of the jacket. The finished construction is shown in section in Fig. 1.

Variations in the precise construction, compositions, loading pressures, etc., which have been illustrated and described may be made, all within the scope of the appended claims.

What is claimed is:

1. A projectile comprising a jacket, a hollow core, a charge of granular difficultly compactible combustible material pressed into and incompletely filling said core, a body of inert pulverant material of low compressibility adapted to coalesce under pressure compacted on said combustible material within and completely filling said core to rigidly secure said combustible material in place therein, and a heel closure secured in said jacket in abutting relation to said core and said body of inert material.

2. A projectile comprising a jacket, a hollow core, a combustible composition within said core, a gas check comprising a body of coalesced inert granular material superposed on said charge and terminating flush with the end of said core, and a heel closure comprising a steel disk and a superposed disk of softer material.
